CLOTHESBRUSH

Charles Arthur Fogarty, Brooklyn, N. Y.

Application September 30, 1952, Serial No. 21,658

Term of patent 14 years

(Cl. D9—2)

To all whom it may concern:

Be it known that I, Charles Arthur Fogarty, a citizen of the United States, residing at Brooklyn, county of Kings, State of New York, have invented a new, original and ornamental Design for a Clothesbrush, of which the following is a specification, reference being had to the accompanying drawing, forming a part hereof.

Fig. 1 is an elevational view of one face of a clothesbrush embodying my new design, the opposite face thereof being the same; and

Fig. 2 is a side elevational view thereof, the opposite side being substantially the same with the exception of the crimped seam which is omitted.

I claim:

The ornamental design for a clothesbrush, as shown and described.

CHARLES ARTHUR FOGARTY.
